UNITED STATES PATENT OFFICE.

CLARENCE A. DIX, OF FOSTORIA, OHIO, ASSIGNOR, BY DIRECT AND MESNE ASSIGNMENTS, TO THE YODER COMPANY, OF CLEVELAND, OHIO, A CORPORATION OF OHIO.

SEAMING-GUIDE DEVICE.

Application filed May 14, 1923. Serial No. 638,883.

This invention relates to a machine for seaming or uniting, by bending together, the edges of sheet metal.

This invention has utility in effecting 5 seaming of sheet steel, as in assembling rims or skirts with fenders for the wheels of motor vehicles.

Referring to the drawings:

Fig. 1 is a side elevation of an embodiment of the invention in a seaming machine 10 as adapted for motor vehicle fender seaming, and similar sheet metal seaming operations;

Fig. 2 is a detail view showing the feed 15 directing guide rolls in working position, as distinguished from the open or inoperative position of the showing in Fig. 1;

Fig. 3 is a front elevation of the machine 20 of Fig. 1; and

Fig. 4 is a side elevation of the invention 25 as adapted to a narrow throat seaming machine, in contradistinction to the wide throat machine of Fig. 1 and

Fig. 5 is a cross-sectional view of the completed seam.

The main machine frame 1 is shown as up- 30 standing to provide a wide throat 2 having an overhanging arm 3 and uprising bracket 4. A continuously running belt 5 serves 35 through pulley 6 when connected by a clutch 7 to operate the seaming machine gearing 8 for driving upper seaming roller 9 and simultaneously rotating the opposing or lower seaming roller 10. The seaming roller 10 is carried by the bracket 4 and the latter is suitably adjusted by hand wheel 11 for 40 properly locating this roller 10 relative to the seaming roller 9 carried by the arm 3. Treadle 12 adjacent the operator's station 45 at the wheel 11 may be depressed to throw in the clutch 7 for effecting driving operation of the seaming rollers 9, 10, in their 50 adjusted coacting relation for rolling interlocking flanges along or provided on adjacent edges of sheet metal stock into snug 55 holding relation. Instead of operating the clutch from the treadle 12, the clutch 7 may be controlled from a suitable handle 13.

In the carrying out of seaming operations, 60 especially with such stiff material as sheet steel, and with the edges to be joined, initially having normally dissimilar courses of extent, due to the special configuration of one or the other, or of both sheets or parts 65 to be joined, there is a great time and labor

70 consuming factor in arranging the two sheets and directing them so that the seaming may be accurate and the travel continuous. As an effective practical solution of this difficulty, 75 controllable positive anti-friction directing means are provided herein. This course 80 may permit even with large heavy skirted front fenders, a starting of the seam and continuous progress, thus avoiding the de- 85 lay of initially wedge blocking, slow hand directing between the blocks, with stops to knock out the blocks. In instances where it is desired to work the stock through the ma- 90 chine either way, the attachment as herein disclosed may be a complete unit installed 95 one upon each side of the machine.

Rising from the base of the main machine 100 frame 1 is a bracket 14 in which is disposed a treadle 15. Depressing the treadle 15 throws the seam directing attachment or de- 105 vice of this disclosure into operative position. From the treadle 15 upwardly extends link 17 to lever 18. This lever 18 carries pin 19 coacting with slot 20, and carries 110 pin 21 coacting with slot 22. These slots 20, 22, are formed in a block 23, which block 23 has a third slot 24. Coacting with the slot 24 is pin 25, which together with the pin 21 are fixed in the bracket 4 and serve to direct 115 the block as shifted by the lever 18. Set 120 screw 26 in auxiliary bracket 27 serves to 125 permit vertical adjustment of guide roller 27' having lower tapering flange or shroud 28. The bracket 27 is adjusted by bolts 29 in its relation to the block 23. As the 130 treadle 15 moves downwardly, pulling the 135 link 17 and swinging the lever 18 on its fixed 140 fulcrum 21, the block 23 is shifted toward 145 the throat 2 with the pin 19 riding into lock- 150 ing portion 30 of the slot 20, thus effecting 155 a positive holding of the sheet metal edge 160 directing guide 27.

From the treadle 15, oppositely movable 165 simultaneously with the link 17, is bent link 31 of a configuration for clearing the throat 17. This link 31 extends to lever 32 having 180 pin 33 coacting with slot 34 and pin 35 co- 185 acting with slot 36 in shiftable block 37. This block 37 has a third slot 38 with which 190 coacts pin 39. The pins 33, 39, serve to 195 mount the block 37 on the arm 3. The lever 200 32 is of the first class, while the lever 18 is of 205 the second class. The block 37 has adjust- 210 ably mounted thereon auxiliary bracket 40, in which is adjustably mounted stem 41 215

carrying upper guide roller 42 having a flange or slight shroud 43 on the upper side thereof remote from its companion guide roller shroud 28. The guide shrouds or flanges 28, 43 serve to direct the traveling sheet stock into the firmly positioning smaller diameter guides proper 27', 42. As the link 31 is moved upwardly, the block 37 is shifted to carry the guide 42 toward the guide 27', the fulcrum pin 33 riding in the slot 34 to locking portion 44, while simultaneously the pin 39 rides in the slot 38 into locking portion 45. Accordingly the block 37 with its guide roller 42 is automatically locked in sheet metal stock directing position when the treadle 15 is depressed, and at the same time the guide roller 27' has been shifted closer and its supporting block 23 locked. It is not necessary for the operator to maintain a foot on the treadle 15, even though the stock being seamed offers considerable resistance to being directed or warped about to conform to the curve variations in the separate sheets.

When the seaming operation is completed, or if for other cause, it is desired to release the directing guide device, it is only necessary that the operator depress the treadle 15. This gives a downward pull on the link 31 and an upward thrust to the link 17. The guide rollers 42, 27', at once shift away from each other to release the stock, or open up for receiving stock.

Inasmuch as the elements of the attachment device are alike on their opposite sides, there is no occasion to work up for rights and lefts in adapting the attachment for either of both sides of a seaming machine.

This same operative arrangement may be adapted to a narrow throat seaming machine of the type illustrated in Fig. 4. A machine frame 46, with a narrow throat 47 is equipped with an adjustable link 48 extending upwardly from treadle 15 for connection by pin 49 to lever 49' having pin 49'' shiftable in slot 50 to locking portion 51 there to hold block 52 carrying the lower guide roller 27'. This block 52 has additional slots 53, 54, respectively coacting with pins 55, 56, fixed in the machine frame 46, which serve positively to direct the block in its shifting to draw the guide 27' into position toward the throat 47 for firmly holding the sheet stock as antifrictionally directed to the seaming rollers 9, 10. The lever 49' has the pin 55 as its fulcrum.

Simultaneously with the throwing of this guide 27', the upper opposing guide 42 is oppositely thrown. From the pin 49 extends link 57 of U-form to clear the throat 47. This link 57 has pivot 58 as a connection to lever 59. As the pin 49 descends, the link descends to swing downward the pin 58 and rock the lever 59 on fulcrum 60 fixed in the

upper overhanging arm of the frame 46. The free or forward end of this lever 59 has pin 60'' which as the lever 59 rocks, swings shiftable block 63, carrying the upper guide roller 42 into positively locked position adjacent the roller 27'. The block 63 has slots 64, 65, with which respectively coat pins 60, 67, for mounting the block 63 to move relatively to the arm 60'. Adjustable mounting means 68, 69, are provided for the guides 27', 42, permitting ready adjustment relative to the blocks 52, and 63 respectively, or replacement.

Due to the great working strain placed upon the guides as herein disclosed, it is important that the travel of the guide or guides for the distance determined to bring the stock into proper directing relation for the seaming be positive, and once the guide is in such proper holding position, during the continuation of such seaming, its position must be maintained. The simple linkages herein effect the shiftings, while the self-locking slot offsets insure the holding during operation.

What is claimed and it is desired to secure by Letters Patent is:

1. A guide mechanism for sheet material seaming rolls embodying a manually controllable member, a pair of guides oppositely of the material as directed to the seaming rolls, a shiftable control block for each guide having self-locking means to maintain the guides in operative position, and linkage from the blocks to the member for controlling the shifting of the blocks into and out of self locking position.

2. A guide mechanism for sheet material seaming rolls embodying a manually controllable member, a pair of guides oppositely of the material as directed to the seaming rolls, a shiftable control block for each guide, each block having a plurality of guide ways for shifting and controlling said block, one of said ways terminally locking the block against shifting of the guides, and linkage from each block control way to said member for effecting movement of the guides.

3. In a seaming mechanism, the combination of a pair of relatively stationary rolls co-operable to seam sheet metal sections together, and means for guiding the sheet metal sections to said seaming rolls, said means comprising a manually controllable member, a guide roller at one side of the seaming rolls, a movable block carrying the roller, said block having directing and control ways, and operating connections from the member including a lever coacting with a control way of the block for effecting movement of said block.

In witness whereof I affix my signature.

CLARENCE A. DIX.
